UNITED STATES PATENT OFFICE.

WILLIAM LINCOLN DUNN, OF OXNARD, CALIFORNIA, ASSIGNOR TO DUNN MANUFACTURING COMPANY, OF OXNARD, CALIFORNIA, A CORPORATION OF CALIFORNIA.

WELL APPARATUS.

1,376,009.

Specification of Letters Patent. Patented Apr. 26, 1921.

Application filed November 17, 1919. Serial No. 338,721.

To all whom it may concern:

Be it known that I, WILLIAM L. DUNN, a citizen of the United States, residing at Oxnard, in the county of Ventura and State of California, have invented new and useful Improvements in Well Apparatus, of which the following is a specification.

This invention relates to oil well apparatus, and more particularly to apparatus for screwing and unscrewing or jointing or unjointing tools used in oil well drilling in the so-called standard or reciprocating drilling method. In this method the tools are suspended by a cable from a walking beam and are given vertical reciprocation in the well, thus cutting, chipping or pounding away the formation and developing the well hole. The tools are connected together in what is called a "string", often including a plurality of such tools, such as bits, sinker bars, stems and jars. In order to screw these together or unscrew them and disconnect them, heavy and powerful wrenches are employed, and it requires considerable power to operate such wrenches. Ordinarily one such wrench is applied to the string of tools beneath a tapered joint, and the other wrench is applied to the tools above such tapered joint or coupling, which tapered joints or couplings it is to be understood are connected with the tools and have screw threads. One wrench is ordinarily held stationary, and the other wrench is operated to produce the rotation requisite to couple or uncouple the tools at such threaded taper joint. In connection with such use of the wrenches what is called a floor circle is ordinarily employed, this consisting of a toothed quadrant or segmental rack mounted upon the floor of the derrick at the mouth of the well. Mounted upon this rack is a toothed ratchet device to which is applied a lever by which the ratchet device is operated to cause it to traverse such segment or rack which is arranged with the string of tools at the center of the segment or quadrant. At one end of this rack is provided a stop against which bears one wrench, and the other, preferably the upper wrench bears against the ratchet device. Thus as the ratchet device is operated along the floor circle or toothed segment it carries with it the outer end of the upper wrench and either screws or unscrews the tools at the

tapered joint. The pressure of the two wrenches upon the ratchet device and the stop mentioned tends to cause the floor circle to wedge or slide inwardly upon the flooring of the derrick and thus reduce the leverage upon the wrenches so as to render the operation of the device difficult or impossible. It will be understood that the long leverage of the long wrench arms is relied upon to give easy and effective action in the lever-produced travel of the ratchet device. So the floor circle must remain at a position so that the ends of the wrench arms, or substantially the ends, bear against the stop and the ratchet device. To prevent this inward creeping of the floor circle and ratchet device, it has been the practice to use blocks or sticks of wood or other make-shift as props or spacers between the string of tools suspended at the mouth of the hole, on the one hand and the floor circle on the other hand. These frequently split and part and fly outwardly or upwardly, thus often causing injury to the operators and drillers, and tending to cause damage in the derrick. I have devised a positive and effective and reliable prop or brace or spacer which is disposed between the tools and the floor circle, and preferably two of these are employed, one adjacent to each end of the floor circle so as to more effectively brace the parts to which it is applied. This brace is adjustable, that is, it comprises a plurality of parts which are relatively adjustable so that different distances between the floor circle and the string of tools may be accommodated; and means is provided for holding the relatively adjusted parts in positions of such relative adjustment. The invention concerns the several parts and features mentioned and their combination and association, and particularly the brace structure, all as hereinafter described, shown in the drawings, and finally pointed out in claims.

The invention consists in the novel and useful provision, formation, combination, association, application and relative arrangement of parts, members and features, all as hereinafter so described, shown and claimed, as above mentioned.

The invention has for its objects to provide improvements of the nature stated which will be superior in point of relative

simplicity and inexpensiveness of construction, taken in conjunction with reliability and positiveness in operation, durability, convenience and effectiveness in use, and 5 general superiority and efficiency and serviceability.

In the drawings:

Figure 1 is a perspective fragmentary view of the flooring of an oil well derrick 10 or rig showing drilling tools suspended at the mouth of the well, and illustrating a floor circle and floor circle brace and wrenches and wrench operating means all in combination for use and constructed in accordance with the invention;

Fig. 2 is a fragmentary longitudinal sectional view taken upon the line x^2-x^2 , Fig. 3, parts being in elevation;

Fig. 3 is a fragmentary top plan view of 20 a floor circle brace such as shown in Fig. 1; and,

Fig. 4 is a detail transverse sectional view taken upon the line x^4-x^4 , Fig. 2, and looking in the direction of the appended 25 arrows.

Corresponding parts in all the figures are designated by the same reference characters.

Referring with particularity to the drawings, A and B designate drilling tools connected by a tapered threaded joint, the joint line being shown at a in Fig. 1. C designates a wrench applied to the tool A, and D designates a wrench applied to the tool B. E designates a toothed quadrant or sector termed in practice a floor circle, at one end of which is shown a ratchet device F having a long power handle G by which the ratchet device may be caused to travel along the floor circle E. H designates a stop at 40 the other end of the floor circle. The long handle c of the wrench C bears against the ratchet device F, and the long handle d of the wrench D bears against the stop H. K designates the floor circle brace or spacer 45 or prop applied between the floor circle E and the upper tool A, bracing the tools at and maintaining them in a fixed relation to the floor circle.

Referring particularly to the details of 50 the floor circle brace, the same comprises two telescoping members m and n , the latter of which is received adjustably within the former, the member m having preferably a pivoted yoke 5 to bear against one 55 of the tools, and the member n having a foot 6 to bear against the floor circle, as in a groove extending lengthwise of the same, one at each side, of which one groove 7 appears in Fig. 1.

60 p designates means for holding the members m and n in positions of relative adjustment, and the members m and n are prevented from disconnection and likewise prevented from relative rotation by a stop pin 65 8 mounted in the member M and projecting

inwardly and received within an elongated groove 9 in the member n .

The member m consists of a length of tubing 10 swaged in to round it at one end, as at 11, with which end is pivotally connected as by a clevis 11^a, the yoke 5 adapted to engage and fit one of the tools. Threaded upon such tubing 10 at the open end, at threads 12, is a collar 13 projecting somewhat beyond the end of the member m and 70 provided with upstanding ears or lugs 14 through which is passed a pin 15 upon which is pivotally mounted a locking finger 16 comprising the means p , one end of which, 16^a, ranges freely above the tubular member m , a coil spring 16^b being disposed between such end 16^a and the member 75 m and tending to force the other end 16^c of the finger, with its plurality of teeth 16^d, into engagement with certain of a plurality or series of teeth 17^a formed or provided longitudinally of the member n which consists of an elongated rod 17. The rod 17 is provided with the foot 6 at its outer end, and its inner end is chambered within the 80 tubular member m , the elongated groove 9 being formed in one side of such rod 17. The toothed end 16^c of the locking finger 16 is downwardly directed in angular relation to the remaining portions of the locking 85 finger, and is adapted to operate through a slot or opening 18 in the top of the collar 13.

The teeth 16^d and 17^a are so formed and coöperate as to oppose movement of the 100 member n inwardly of the member m , but to permit the drawing out of the member n or its extension from the member m , the locking finger 16 in such latter case playing pivotally against the compression of the 105 spring 16^b.

The stop bolt 8 is screwed into the side wall of the collar 13.

In use, it will be understood that the prop or brace K is placed in position with 110 the foot 6 in the channel or groove 7 on the inner face of the toothed sector E, the teeth 7^a of which sector or floor circle are traversed in the usual manner by the walking ratchet device F. The 115 yoke 5 is brought to bear against the upper tool A, the member n being drawn out of the member m until it properly braces the tools with respect to the floor circle, the locking means or locking finger p automatically acting to interlock the two members m and n in their proper condition of extension, by telescopic adjustment, when the tools are properly braced or propped. The wrenches C and D being properly applied 120 to the tools and to the ratchet device F and the stop device K at opposite ends of the floor circle E, the ratchet device is now operated to carry around the long arm c of the upper wrench C. The lower tool is 125 130

held stationary by the wrench D, and thus the tools are threaded together. The reversal of the operation, or reversing the wrenches, will of course cause the unscrewing or disconnecting or disjointing of the tools. It is to be understood that when the ratchet device has executed one journey along the floor circle it is brought back, the working wrench is re-applied to the proper tool, and the operation is repeated and continued until the complete jointing or unjointing action has occurred.

The floor circle brace or prop K is compact in form and simple to adjust and manipulate, and is durable and reliable in action and readily adapts itself to the conditions met with in service. When it is desired to disconnect the brace from its position of service the inner end 16^a of the locking finger 16 is depressed, withdrawing the teeth 16^a from the teeth 17^a, whereupon the member n is permitted to further chamber within the member m, shortening up the length of the entire brace, whereby it may be removed from position. It may be lengthened out or shortened up readily as conditions require, the locking finger 16 being manipulated to permit the shortening up action, and automatically accommodating the lengthening out action, the co-acting locking teeth 16^a and 17^a maintaining the members in their relative positions of relative adjustment. The stop bolt 8 in its coöperation with the walls and extremities of the groove 9 keeps the members m and n in proper relation, preventing axial displacement or movement, and likewise prevent an overplay or over-extension of the member n in its telescoping movements in the member m.

I have indicated in dotted lines in Fig. 1 the provision of another brace member K between the floor circle E and the tools. This is to make it clear that there may be a plurality of such braces employed, and it is often preferable to dispose one of the same adjacent to the stop H and another of the same adjacent to the other end of the floor circle, so as to provide the bracing action adjacent to the ends of the floor circle and where the tendency of the floor circle to wedge inwardly along the wrench handles is pronounced or effective.

It will be obvious that many variations and modifications of the structure may be resorted to in adapting the device to varying conditions of use and service, all without departing from the true spirit of the invention.

Having thus disclosed my invention, I

claim and desire to secure by Letters Patent:

1. In well apparatus, a floor circle brace comprising two telescoping members, and locking means for maintaining the same in position of relative adjustment, said locking means comprising a part threaded adjacent to the end of one of said members and carrying a locking finger having a downwardly directed end portion provided with a plurality of transverse teeth, the other telescoping member being transversely toothed and adapted to co-act with said first named teeth to form a strong gripping action; the said teeth being so formed as to resist compressive effort between the telescoping parts; one of said telescoping members being provided with an elongated grooved portion, and the other telescoping member being provided with a projecting pin for engagement with said grooved portion, thereby limiting telescopic action of said members in one direction and likewise preventing relative axial play of said members.

2. In well apparatus, a floor circle brace, comprising two telescoping members one of which is provided with a foot adapted to engage the floor circle and the other of which is provided with a yoke adapted to engage one of the tools; said telescoping members likewise being provided with locking means for maintaining the same in position of relative adjustment, said locking means comprising a part threaded adjacent to the end of one of said members and carrying a locking finger having a downwardly directed end portion provided with a plurality of transverse teeth, the other member being transversely toothed and adapted to co-act with said first named teeth to form a strong gripping action; said teeth being so formed as to resist compressive effort between the telescoping parts; one of said telescoping members being provided with an elongated grooved portion, and the other telescoping member being provided with a projecting pin for engagement with said grooved portion, thereby limiting telescopic action of said members in one direction and likewise preventing relative axial play of said members.

In testimony whereof I have signed my name to this specification in the presence of two subscribing witnesses.

WILLIAM LINCOLN DUNN.
